Primary Examiner — Ralf Seifert(74) *Attorney, Agent, or Firm* — M. Kala Sarvaiya; Steven C. Sereboff; SoCal IP Law Group LLP(57) **CLAIM**

The ornamental design for a mobile head mounted display controller, as shown and described.

DESCRIPTION

FIG. 1 is a front, top and left side perspective view of a mobile head mounted display controller.

FIG. 2 is a rear, bottom and right side perspective view thereof.

FIG. 3 is a top plan view thereof.

FIG. 4 is a bottom plan view thereof.

FIG. 5 is a left side elevation view thereof, with the right side elevation view being identical to the left side elevation view.

FIG. 6 is a top plan view thereof; and,

FIG. 7 is a bottom plan view thereof.

The broken lines shown in the drawings are for illustrative purposes only and form no part of the claimed design.

1 Claim, 3 Drawing Sheets(56)
